A.M.

UNITED STATES PATENT OFFICE.

DANIEL PETARD, OF NICE, FRANCE.

SAFETY RAZOR.

Application filed June 25, 1924, Serial No. 722,224, and in France February 27, 1924.

My invention relates to improvements in safety razors furnished with a flexible blade clamped between a guard plate and a backing plate of curved section.

According to this invention, between the blade and the guard a spacing plate is inserted, the curvature of which corresponds to that of the guard and which has on its upper surface (that which does not come in contact with the guard) some suitably formed hollowed out places.

This plate is intended to separate or put the blade apart from the guard and to prevent the fouling of the apparatus by facilitating the rinsing and cleaning of the same. It is adaptable to all existing apparatus, enabling such to be transformed and improved according to the present invention.

The annexed drawing given by way of example shows one of the methods of carrying out this invention.

Fig. 1 is a plan view of the spacing plate.

Fig. 2 a transverse section along the line A—A (Fig. 1).

Fig. 3 a section along the line B—B in Fig. 1.

Fig. 4 an end view.

Fig. 5 a longitudinal central section.

Fig. 6 a front view.

Fig. 7 a longitudinal section of a razor equipped with the plate.

Fig. 8 is an end view.

The spacing plate 1 is curved so that it can be applied to the guard 2 (Figs. 7 and 8) of a safety razor of well known construction. This spacing plate has on its convex side hollowed out places 1^a forming projecting parts with curved edges 1^b (Fig. 1).

The curvature of these projecting edges is intended to facilitate the passage of hair and soap when the apparatus is being used.

Holes 3 are formed in the plate for the passage of the positioning pins and the central stem or rod of the backing plate 4 (Fig. 7) employed in razors of this kind.

As is seen in Figs. 7 and 8 the spacing plate 1 is arranged between the usual flexible blade 5 and the guard 2, the projecting parts of the plate being in contact 50 with the blade and its smooth concave part bearing on the guard.

When the razor is clamped (by turning the nut 6) the plate 1 keeps the blade 5 and the guard 2 a certain distance apart 55 (equal the full thickness of the plate 1). In consequence of this, the blade has an increased cutting power without the apparatus losing its safety qualities.

Moreover, owing to the hollowed out 60 places 1^a in the plate, the fragments of hair and the soap can readily move below the blade. This prevents the fouling of the apparatus and facilitates the rinsing and cleaning of the razor.

It is quite understood that these hollowed out places which are only an improvement in the original object of the plate which is the elevation of the blade above the guard, may be shaped other than shown in the 70 drawing, it being understood that for super-elevating the blade a few points of thickness between the blade and the guard will suffice.

Obviously, other methods and other forms 75 of construction can be resorted to without a change in the nature of this invention. Likewise the details of manufacture may also be modified. It is also understood that any material capable of serving for this manufacture may be employed.

I claim:

For use on safety razors of the Gillette type, a concavo-convex spacing plate adapted to be interposed between the blade and 85 the curved guard and provided on its convex face with recesses forming separated elevated portions having curved edges and each constituting a support for the razor blade.

In testimony whereof he has affixed his 90 signature.

DANIEL PETARD.
